UNITED STATES PATENT OFFICE.

CHARLES FRANCIS JENKINS, OF WASHINGTON, DISTRICT OF COLUMBIA.

PICTURE-PROJECTING DEVICE.

1,090,622.

Specification of Letters Patent. Patented Mar. 17, 1914.

Application filed March 20, 1913. Serial No. 755,750.

To all whom it may concern:

Be it known that I, CHARLES FRANCIS JENKINS, a citizen of the United States, residing at Washington, District of Columbia, have invented certain new and useful Improvements in Picture-Projecting Devices, of which the following is a specification, reference being had therein to the accompanying drawing.

10 This invention relates especially to devices which produce light and project it through a film or plate to show motion or other pictures, all the parts being carried by a casing from which they may be readily removed, 15 and its principal objects are to provide a light, convenient and compact apparatus which delivers light uniformly with less than the usual heat and which may be operated even by children without serious danger of injury to themselves or others.

In the accompanying drawings, Figure 1 is a plan view of the apparatus. Fig. 2 is a partial section on the line 2—2 of Fig. 3. Fig. 3 is a section on the line 3—3 Fig. 2.

25 In these figures, A represents a casing consisting of a rectangular sheet metal box, having a support A', open at one end and closed at the other by an upwardly removable sliding sheet metal plate A². To this 30 plate are secured birding posts B, B, a sight glass B', and holders C C adapted to carry at right angles two small slidingly adjustable carbons D, D projecting within the body of the casing. At the opposite end 35 the casing is provided with a rectangular lens frame E having ways E' in which ordinary picture bearing plates may rest when stationary pictures are to be projected, and in this frame separated circular lens members F are held at their quadrantal points, 40 leaving open air spaces G at the four angles of the frame which fits the casing but is readily withdrawn bodily therefrom. In the central portion of the casing is a similarly removable tubular drum having at each 45 end rectangular flange members H which fit the interior of the casing and are connected by an open sheet metal cylinder or drum body H'. Upon the body H', which 50 bears insulating material H² is spirally wound a wire coil I forming a rheostat to control the current through the carbons, the holders of which are connected to the ends of the coil by wires J, J', respectively. Below 55 the arc space the casing is provided with a series of small apertures K and above it is

a larger opening L protected by a hood L'. The casing is also perforated above and below the rheostat, so that cooling air may pass around the drum.

The carbons are small and the lens members are large and naturally, they absorb much heat from the beam passing through them. Air, however, constantly passes somewhat rapidly around them, through the hollow drum, absorbing heat from that also, and thence through the hood above the arc to the open air. The lens members never become highly heated and the heat which they give up to the air bears a direct ratio to their own temperature, the practical result being that the projected beam of light is never dangerously hot, and a properly arranged film can never be ignited thereby. It is also to be observed that the rheostat occupies space not otherwise utilized and thus adds nothing to the space occupied by the apparatus, and further that its heating is not material to the operator or others, for contact with it is prevented. The light is produced by current not in any case especially dangerous, and, like the rheostat, the arc cannot be accidentally reached by anything. All that is necessary for installation is to connect the usual incandescent light wires to the binding posts and strike the arc by adjusting the carbons.

Practically, all danger from fires is eliminated as well as all danger of personal injury, and withal the apparatus is extremely simple, light, and inexpensive, and at the same time unusually convenient in transportation and use.

What I claim is:

1. In apparatus of the class described, the combination with an electric light, a projecting lens, a rheostat in series with the light, and a casing inclosing the light, lens and rheostat, the parts being arranged to permit cooling air to pass freely into the casing, upwardly through the interior chamber, and out of the casing.

2. In apparatus of the class described, the combination with a casing or box, of a rear electric light, a front projecting lens and an intermediate rheostat in series with the light, all inclosed by the casing, said casing having apertures to permit cooling air to pass freely upward through the rear end of the box and to allow the escape of cooling air entering around the lens.

3. The combination with a sheet metal

casing having near one end an inclosed externally regulated arc light and provided with openings below and above the light for the entrance and escape of cooling air, of a lens inclosed in the casing near its opposite end and held by devices allowing air to pass freely over its edge and face surfaces, and a rheostat also inclosed in the casing and arranged to be cooled by air currents which have passed over the lens surfaces.

4. The combination with a sheet metal casing, of an arc light mounted in one end portion of the casing, a projecting lens mounted in the opposite end of the casing in

a frame permitting cooling air to pass freely 15 over its edges at various points, and a tubular rheostat in the path of cooling air, passing rearward from the lens, and outside the path of light passing to the lens, said casing having perforations above and 20 below said light and rheostat to allow free passage of cooling air.

In testimony whereof I affix my signature in presence of two witnesses.

CHARLES FRANCIS JENKINS.
